Thomas J. Chambers

UNITED STATES PATENT OFFICE.

GEORGE S. STRONG, OF NEW YORK, N. Y., ASSIGNOR TO THE BALANCED LOCOMOTIVE AND ENGINEERING COMPANY, OF SAME PLACE.

COMPOUND ENGINE.

SPECIFICATION forming part of Letters Patent No. 559,502, dated May 5, 1896.

Application filed November 17, 1894. Serial No. 529,110. (No model.)

To all whom it may concern:

Be it known that I, GEORGE S. STRONG, a citizen of the United States, residing in the city, county, and State of New York, have invented a certain new and useful Improvement in Compound Engines, of which the following is a true and exact description, reference being had to the accompanying drawings, which form a part thereof.

10 My invention relates to compound engines, and has for its object to improve and simplify the construction of such engines and render them more compact.

15 My invention will be best understood as explained in connection with the accompanying drawings, in which—

Figure 1 is a front view, in vertical section, of a quadruple expansion-engine embodying my improvements. Fig. 2 is a vertical section on the line $x-x$ of Fig. 1, and Fig. 3 is a cross-section on the line $y-y$ of Fig. 1.

20 F is a suitable frame on which are supported the crank-shaft S, the cylinders, and the other operative parts of an engine.

25 C is a casting having formed therein a cylinder c , suitable cores for valves u v , and is provided with a suitable flange, which is preferably formed in two parts f f' .

30 C' is a casting very similar in form to the casting C, having formed therein a cylinder c' of larger cross-section than the cylinder c , suitable cores for valves, and is provided with a flange adapted to abut against the flange on the casting C. This flange is also conveniently formed in two parts f' f'' .

35 The faces of these flanges are planed off true, and when the castings are in position these flanges abut, as shown in Fig. 3, and the castings are bolted together. In the construction shown I also

40 form recesses f'' f''' in the flanges, which serve as guides for a valve-stem s. A casting C², having a cylinder c^2 formed therein, forms the head of the cylinder c , and a casting C⁴, having a cylinder c^4 formed in it, forms the

45 head of the cylinder c^2 . Similar castings C³ C⁵, with cylinders c^3 c^5 , are similarly arranged over the cylinder c' . I preferably form the cylinders c^4 c^5 of the same size, and also the cylinders c^2 c^3 , these last-named cylinders being larger than the cylinders c^4 c^5 .

50 A is a piston adapted to reciprocate in the

cylinder c , and is provided with trunk extensions b b^2 , preferably of the same size, the trunk b^2 extending into and forming with its head a^2 the piston in cylinder c^2 , while the 55 trunk b serves as a cross-head guided in neck D and sleeve H. From the end of the trunk b^2 another trunk b^4 extends into the cylinder c^4 and forms the piston in that cylinder. A similar piston A', provided with similar 60 trunks b^3 , b' , and b^5 , is arranged in the parallel set of cylinders c^3 c^5 . The pistons in the cylinders c^4 c^5 are preferably of the same size. So are the pistons in the cylinders c^2 c^3 , and these pistons are all single-acting. A single 65 valve V, preferably a tubular piston-valve, as shown, is adapted to govern the admission of steam to and its exhaust from these cylinders c^2 c^3 c^4 c^5 , which, it will be observed, form of themselves a compound engine, and these four 70 cylinders, arranged substantially as shown, form a very efficient single-acting engine, and may be used as such independent of the cylinders c c' , which form a second compound engine.

75 In the position of the valve N (shown in Fig. 1) steam at high pressure from the port N' enters the cylinder c^4 through the port o^4 . Steam at the same time is exhausting from the cylinder c^5 into the tubular valve V and 80 through the openings v^4 and port o^2 into the cylinder c^2 , and finally the steam from the cylinder c^3 is exhausting out of port o^3 and port N'. The steam is preferably exhausted from the upper cylinders into a receiver K, 85 from which it is taken to be further expanded in the lower pressure-cylinders. This receiver K, I prefer to make also a reheat, and I therefore provide a tube-plate k, preferably in the lower part of the receiver K, in which 90 the tubes are secured. K' is a closed box not connected with the casing of the reheat K, into which box the tubes l l open. k² k³ are covers of the box K' and the reheating-receiver K, respectively.

95 K is a pipe for the admission of superheated steam or other hot gas for reheating the partially-expanded steam in the reheat, and k⁴ is a drip-pipe which may lead to a trap.

100 By my construction of the reheat it will be seen that no expansion which the tubes can be subjected to will have any effect on

the casing, as the box K' is independent of this casing.

The space around the tubes 11 forms part of the passage of the steam from the upper 5 cylinders to the lower, and the steam, after being superheated, passes through the passage N² and is admitted alternately into the upper and lower ends of the cylinder c by means of valves u v. The steam after being 10 expanded in the cylinder c passes through the passages o p, extending from the top and bottom of the cylinder c, respectively, and is admitted into the top and bottom of the cylinder c' by means of valves u' v', respectively, 15 u' v' being exhaust-valves through which the steam flows to the final exhaust-passage O. The valves u v, &c., for the lower cylinders are substantially the same and are operated in substantially the same way as the valves 20 described and claimed in my application, Serial No. 529,109, filed November 17, 1894, and I therefore do not claim the arrangement or mode of operating these in this application. While, as I have said, the single-acting cylinders c² c³ c⁴ c⁵ can be used by themselves, I 25 prefer to combine them with the double-acting cylinders c and c', thus making a quadruple expansion-engine which is very compact and easily operated.

30 The piston A, I preferably form of an annular ring a, and form a cylinder b b² of thin metal, preferably steel boiler-plate, which cylinder is adapted to extend in both directions, forming trunks, as has been explained. This 35 cylinder b b² I turn up on the outside so that it will fit the cylinder c³ and the inside of the ring a. Then it is turned up on the inside and a spider L fitted therein. When in position, the spider L is secured to the ring a, as 40 by rivets, securing all the parts together.

The piston-head a² has formed on it a flange l², which fits the upper end of the cylinder b b², and at the lower end I secure a plate l', to 45 which is secured the connecting-rod G by means of the pin g. This construction produces a very light piston and may of course be duplicated in the other set of pistons.

To guide the trunk extensions b b', I provide necks D on the cylinders c c' and also 50 sleeves H, conveniently centered by means of suitable flanges h², which are seated in grooves d² in the frame of the engine. The sleeves H have grooves h, in which are seated packing-rings r, which embrace the trunks b b', 55 and, as will be seen, the neck D and sleeve H form in effect a cylindrical cross-head guide for the trunk extension b.

The two connecting-rods G are connected to cranks S' on the main shaft.

60 E is an eccentric, S² a link having a slot S³, in which is arranged a block S, and serves by means of rod s² and stem s to operate the valve V, and by means of the rod S⁶ to operate the valve u v, &c.

65 Having now described my invention, what I claim as new, and desire to secure by Letters Patent, is—

1. The combination in a compound engine of a casting C having a cylinder c formed therein and provided with flanges f f², with a casting 70 C' having a cylinder c' formed in it and provided with flanges f' f³ corresponding to the flanges f f² on the casting C, said flanges having recesses f⁵ f⁶ adapted to form guides for a valve-rod s.

2. In a compound engine the combination with the double-acting cylinders c c' arranged side by side and having steam-ports adapted to admit steam at the top and bottom of said cylinders, of cylinders c² c³ of decreasing areas 80 arranged over the cylinders c c' respectively and having steam-ports o² o³ for admitting steam to the top of the cylinders, and cylinders c⁴ c⁵ of decreasing diameters arranged over the cylinders c² c³ having ports o⁴ o⁵ for 85 admitting steam into the top of the cylinders c⁴ c⁵ all substantially as specified and so that the cylinders c⁴ c⁵ and c² c³ can serve as single-acting and the cylinders c c' as double-acting cylinders.

3. The combination with the cylinders c⁴ c² c arranged in line with each other of the cylinders c⁵ c³ c', also arranged in line with each other, the cylinder c⁴ being of the same size as the cylinder c⁵ and the cylinder c² of the 95 same size as the cylinder c³, ports adapted to admit steam to the cylinders so that the cylinders c c' will act as double-acting and the other cylinders as single-acting cylinders and trunk-pistons for said single-acting cylinders. 100

4. In a compound engine a double-acting piston A having trunks b b² extending from it in opposite directions b² being a piston and b a cross-head and a trunk-piston a⁴ extending from the trunk-piston b² in combination with 105 a piston A' having trunks b' b³ extending from it on opposite sides b³ being a piston, and b' a cross-head and a trunk b⁵ extending from the trunk b³ and suitable cylinders for said pistons.

5. In a compound engine a piston A having trunks b b² of equal size extending from it in opposite directions b² being a piston and b a cross-head and a trunk-piston a⁴ extending from the trunk-piston b² in combination with 115 a piston A' having trunks b' b³ of the same size as the trunks b b² extending from it on opposite sides b³ being a piston and b' a cross-head and a trunk-piston b⁵ extending from the trunk-piston b³ suitable cylinders for said pistons and cylindrical cross-head guides for the trunks b and b'. 120

6. The combination with a double-acting piston A of a thin metal cylinder b² extending in one direction and serving as a trunk-piston 125 and a similar cylinder b extending in the other direction and serving as a cross-head, a trunk-piston head a² secured to the cylinder b² a plate B⁴ secured to the cylinder b and a connecting-rod G secured to the plate B⁴.

7. The combination with an annular double-acting piston A, of a thin metal cylinder b b² extending through the annular piston A and forming trunk extensions on each side thereof,

a spider L inside the piston A and a piston-head a^2 having a flange l^2 fitting in the upper part b^2 of the cylinder.

8. The combination with cylinders $c^3 c^4$ and $c^5 c^6$ provided with suitable pistons and adapted to act as a compound engine, a valve for governing the flow of steam to and from said cylinders, a cylinder c in line with the cyl-

inders $c^3 c^4$ a cylinder c' in line with the cylinders $c^3 c^5$ the cylinders $c c'$ being adapted to act as a compound engine, and a receiver between the two sets of cylinders.

GEORGE S. STRONG.
